(57) **CLAIM**

The ornamental design for a toss target rack, as shown and described.

DESCRIPTION

FIG. 1 is a perspective view of a toss target rack, showing the first embodiment of my new design;

FIG. 2 is the second perspective view thereof;

FIG. 3 is a front elevational view thereof;

FIG. 4 is a rear elevational view thereof;

FIG. 5 is a left side view thereof, the right side view being a mirror image of FIG. 5;

FIG. 6 is a top side view thereof, the bottom side view being a mirror image of FIG. 6;

FIG. 7 is a perspective view of a toss target rack, showing the second embodiment of my new design;

FIG. 8 is the second perspective view thereof;

FIG. 9 is a front elevational view thereof;

FIG. 10 is a rear elevational view thereof;

FIG. 11 is a left side view thereof, the right side view is identical;

FIG. 12 is a top plan view thereof; and,

FIG. 13 is a bottom plan view thereof.

The broken lines in the figures are for the purposes of illustrating portions of the toss target rack, which form no part of the claimed design.

1 Claim, 12 Drawing Sheets
